Kubert & Peck

Attorney

UNITED STATES PATENT OFFICE.

WILLIAM F. PATTEN, OF WASHINGTON, DISTRICT OF COLUMBIA.

SYRINGE.

Application filed September 22, 1926. Serial No. 136,991.

This invention relates to certain improvements in syringes; and the nature and objects of the invention will be readily recognized and understood by those skilled in the arts involved in the light of the following explanation and detailed description of the accompanying drawings illustrating what I at present consider to be the preferred embodiments or mechanical expressions of my invention from among various other forms, arrangements, combinations and constructions of which the invention is capable within the spirit and scope thereof.

The invention is particularly directed to syringes employed for hypodermic injections in the practice of medicine and dentistry, and is more specifically concerned with such syringes when of those types embodying a glass barrel or cylinder within which a glass plunger or piston is operatively mounted for drawing a charge into the barrel and for ejecting or forcing the charge therefrom in performing a hypodermic injection, although the invention is not limited to such types of syringes or to the materials of which formed.

These types of hypodermic syringes are generally typified by a ground glass plunger rod of the same diameter throughout its length which is very accurately ground to form a close running fit with and in the syringe cylinder or barrel to provide a piston therefor, and in operation and use these plunger rods or pistons frequently fall or slide out and drop from the syringe barrels and are broken, soiled or otherwise rendered unfit for further use. Due to the very accurate fit required of these plunger rods they are expensive and often difficult to quickly replace, and where no replacement is immediately accessible and an emergency calls for immediate use of a hypodermic syringe, serious consequences to a patient can result.

One of the fundamental objects of the present invention is to eliminate possibility of a syringe plunger rod or piston falling or being accidentally displaced from a syringe, as well as to provide for ready control of the plunger position in the syringe barrel where and when desired.

Another object of the invention is to provide for maintaining a syringe plunger rod or piston against accidental displacement from a syringe barrel, through frictional engagement of the rod with an element formed from and as a part of the syringe.

Another object of the invention is to provide a resilient member for frictionally engaging the plunger or piston rod of a syringe to prevent accidental displacement of the rod and for holding the rod in a desired position, which member is so designed, formed and mounted as to in no way interfere with the normal use and operation of the syringe, and which will not mar, scratch or otherwise injure the surface of the rod frictionally engaged thereby.

A further object of the invention is to form and provide a member for frictionally engaging a syringe plunger rod to prevent accidental displacement of the rod, from and as an integral part of the rubber or other material head of the syringe grasped by the fingers in operating the syringe and used as a stopper or plug for a container in filling a syringe.

With the foregoing general objects and certain other objects in view, which will be readily apparent to those familiar with the art from the following explanation, the invention consists in certain novel features in construction, and in combination and arrangement of parts, as will be more fully and particularly referred to and specified hereinafter.

Referring to the accompanying drawings in which similar reference characters refer to corresponding parts throughout the several figures thereof:

Fig. 1, is a view in elevation of a syringe filling container with a syringe mounted therein and a resilient member of the invention formed from the rubber syringe head and container stopper, in frictional engagement with the syringe plunger rod in accordance with the invention.

Fig. 2, is a vertical longitudinal section through the container and syringe of Fig. 1, with the plunger rod raised and showing the rod engaging member of the invention in operative position.

Fig. 3, is a top plan view of the container and syringe and of the member engaging the plunger rod, with the latter in section taken on line 3—3 of Fig. 2.

Fig. 4, is a side elevation of the stopper forming rubber head of the syringe showing the rod engaging member formed therefrom in position prior to bending upwardly into operative rod engaging position, and disclosing the cut or incision through the head by which the member is formed therefrom.

Fig. 5, is a side elevation of the stopper forming head of the syringe and head of the plunger rod, with a modified form of rod engaging member formed on and from the syringe head.

Fig. 6, is a top plan view of the head and member of Fig. 5, with the plunger rod in transverse section and operatively engaging the member.

10 A form and type of hypodermic syringe is presented herewith embodying a glass barrel or cylinder and a glass plunger or piston rod mounted therein, together with a rubber syringe head which is grasped by the fingers 15 in operating the syringe and which also forms a stopper or closure in filling the syringe from a container. However, the disclosed type of syringe is purely by way of example and not of limitation, and is selected 20 because it presents the problem and difficulties overcome by the invention in a high degree and thus serves to more clearly illustrate and bring forth the invention, the principles and features of which are capable 25 of general application to syringes and the like of other forms, types and materials, as will be readily recognized by those skilled in this art.

In the example hereof, referring now to 30 Figs. 2 and 4 of the drawings in particular, a hypodermic syringe is disclosed which includes the glass barrel or cylinder 10 having the hypodermic needle 11 at the discharge end thereof and the opposite end open 35 to receive a plunger rod and formed with a radial flange 12 extending therefrom and therearound. A ground glass plunger rod 14 is slidably fitted into the open end of the syringe barrel 10 and extends thereinto 40 to form a tight running fit therewith and provide the piston or plunger for drawing a charge of liquid into the barrel and for ejecting the same therefrom through the needle 11 at the discharge end of the barrel 10. The outer end of plunger rod 14 is 45 formed with the operating head 15 for engagement by the hand, usually the thumb thereof, to force the rod inwardly and eject a charge from the barrel. The plunger rod 50 14 is of the same diameter throughout its length and is very carefully and accurately ground to form the required tight but freely 55 sliding fit with the inner surface of the barrel 10. In practice it is found, particularly 60 when the syringe is held with the needle 11 in elevated position, that the rod 14 frequently slides and drops from the barrel 10 and is 65 broken or otherwise rendered unfit for further use, as will be readily recognized by 70 those familiar with such types of syringes.

At the operating or plunger rod receiving 75 end of barrel 10 of the syringe, in the present example, a rubber head or stopper 16 is mounted thereover and therearound, the head 80 16 being formed with an axial bore receiv-

ing and through which the syringe barrel 10 extends. In mounted position the rubber head 16 fits up against and receives the flange 12 of barrel 10, and is formed adjacent its lower end with the circumferential bead 17, 70 as will be clear by reference to Fig. 2 of the drawings in particular. This head 16 forms a hand or finger hold in the operation of the syringe in carrying out an injection therewith as will be clear to those skilled in the art, and further forms and provides a stopper for positioning the syringe in and closing a container from which the syringe is to be filled. For example, in Figs. 1 and 80 2, a container 18 is shown in the form of a tube closed at one end and open at the opposite end with a flaring mouth and a groove 19 therearound. The charge for the syringe is placed in the container 18, and the syringe barrel is inserted and extended into container 18 with the stopper or rubber head 16 fitting into and closing the container and positioning the syringe therein. The bead 17 of the syringe head 16 fits into groove 19 of the container and holds the head 16 in closing position against displacement, so that the rod 14 can be slid or moved outwardly through syringe barrel 10 and the desired charge drawn thereinto.

Now, according to the invention, a member 95 20 is provided frictionally engaging the plunger rod 14 to prevent accidental displacement thereof from barrel 10, but without interfering with the normal operation of the plunger rod or handling of the syringe 100 in performing an injection. This member 20 is formed from the rubber head or stopper 16 by transversely slitting or cutting through the head a distance below the outer end thereof, in this instance at a distance approximately equal to the depth or thickness of barrel flange 12, although not so limited, and terminating inwardly or transversely through the head a distance slightly beyond the longitudinal center of the stopper bore and the plunger rod 14. The cut or incision through head 16 to form member 20 is shown at 21 in Fig. 4 of the drawings, and will be understood by reference thereto. The member 20 is then raised and bent upwardly and outwardly from the body of head 16, to form in effect an outwardly extended bridge over and across one side of the open end of syringe barrel 10 with the outer cross portion of the member providing a bar for engaging the plunger rod.

The syringe plunger rod 14 is inserted into the barrel 10 with the member 20 bearing against the rod under tension to frictionally engage the same, due to the resiliency or elasticity of the material from which formed, and prevents accidental displacement of the rod from the syringe barrel, as well as maintaining the rod at any desired position in the barrel. The material from which mem-

ber 20 is formed will not scratch, mar or otherwise injure the accurately ground surface of rod 14, yet will exert sufficient pressure thereon to frictionally engage the rod 5 and prevent its dropping from the syringe, without interfering with the normal operation of the plunger rod. The friction or holding effect of member 20 is intensified because of the ground glass surface of rod 14 10 engaged by the rubber surface of the member, as will be readily apparent. The member 20 does not project laterally beyond the syringe head and is so designed as to in no way interfere with the usual handling of 15 the syringe or the functions of the syringe head 16.

A modified form of frictional engaging member 22 is disclosed in Figs. 5 and 6 of the drawings, in which form member 22 is 20 formed as an integral projection extending from the outer side of head 16 and inclined inwardly toward and a distance over and above one side of the open end of the syringe barrel for engagement with the plunger rod 25 14. In the example hereof, the outer free end of member 22 is provided with a transverse groove or notch 23 to receive plunger rod 14, and the member is so designed that it is pressed outwardly with the rod in position and is thus maintained under and exerting tension on and against the rod. Obviously, the head 16, can be formed of other materials than rubber, or the member 22 can be formed as a separate element of the same 30 or different material from head 16, and embedded or secured therein, and the invention includes and contemplates such formations and mounting of the member.

It is also evident that various changes, 40 modifications, variations and substitutions might be resorted to without departing from the spirit and scope of my invention and hence I do not wish to limit myself to the exact and specific disclosures hereof.

45 Desiring to protect my invention in the broadest manner legally possible, what I claim is:

1. In a syringe, including a barrel and a plunger therein, a head on the barrel adapted 50 to form and be positioned as a closure for a container for positioning the syringe therein, and a member formed from said head frictionally engaging the plunger to prevent

accidental displacement thereof from the barrel. 55

2. In a syringe embodying a barrel and a plunger rod slidably extending therein, a head on the barrel, and a relatively soft, resilient material member on the head frictionally engaging the extended end of the 60 plunger rod.

3. In a syringe embodying a barrel, and a plunger rod slidably extending therein, a rubber head on the barrel, and a member formed from and integral with said head 65 frictionally engaging the extended end of the plunger end.

4. In a syringe embodying a barrel and a plunger rod therefor, a head surrounding the end of the barrel through which the plunger 70 rod extends, and a soft, resilient material member on the outer side of said head frictionally engaging the outwardly extending portion of the rod.

5. In a syringe embodying a barrel and a 75 plunger rod slidably extending therein, a head of soft, resilient material on the barrel at the end through which said rod slidably extends, and a portion of said head extended outwardly and frictionally engaging said 80 plunger rod.

6. In a syringe embodying a barrel and a plunger rod slidably mounted therein and extending outwardly through one end thereof, a rubber head on the barrel around the 85 end thereof through which said rod extends, and a portion of the outer end of said head severed and bent outwardly to form a member bearing against said rod under tension and frictionally engaging the same. 90

7. In a syringe embodying a barrel and a plunger rod slidably mounted therein and extending outwardly through one end thereof, a rubber head around the end of the barrel through which said rod extends, said 95 head formed with a transverse cut extending partially therethrough adjacent the outer side thereof and terminating inwardly adjacent the opposite side of the barrel, and the portion of the outer end of the head over 100 said cut bent outwardly to form a member bearing against and frictionally engaging the outwardly extended plunger rod.

Signed at Washington, D. C., this 18th day of Sept., 1926.

WILLIAM F. PATTEN.
